Letters Patent 2039, dated March 21, 1865

Design for a Trade Mark

The whole referred to in these Letters Patent and making part of the same.

To all whom it may concern:

Be it known that I, James Scty, of the City, County and State of New York, have invented, or produced a new and ornamental Design for Trade Mark; and I do hereby declare that the following is a full, clear and exact description thereof, which will enable others skilled in the art to make and use the same, reference being had to the accompanying drawing forming part of this specification.

The drawing represents a front elevation of this invention. The design consists in a bird rising from a fire with spread wings and its head half turned back towards the rays of the sun rising in its rear. The word trade mark is written under the bird in black letters, the whole being so arranged as to produce an ornamental appearance of such a nature that it can be readily distinguished from other trade marks.

A represents a bird rising from the fire. B. The wings a of the bird are spread as shown and its head b is half turned back towards the rays of the sun rising behind.

The beak c of the bird is partially open intanding

DES. 2039

2 to show that the same cause out for joy over its new life and the wings are slightly turned and just in the position to descend and to give a new upward impulse to the bird.

The talons and lower part of the body of the bird are concealed in the fire, and under the wings of the bird on both sides of the fire is written the word trade mark, thus showing the object of the design.

I claim as new and desire to secure by Letters Patent.

A design for a trade mark as shown and described.
